UNITED STATES PATENT OFFICE.

EDWIN B. STIMPSON, OF NEW YORK, N. Y.

IMPROVEMENT IN PRESSES FOR PERFORATING SHOE-TIPS.

Specification forming part of Letters Patent No. 105,382, dated July 12, 1870.

To all whom it may concern:

Be it known that I, EDWIN B. STIMPSON, of the city, county, and State of New York, have invented a new and useful Improvement in Presses for the Perforation of Shoe-Tips and other Articles, of which the following is a full, clear, and exact description, reference being had to the accompanying drawings, forming part of this specification, and in which—

Figure 1 represents a front elevation of my improved press; Fig. 2, a partly-sectional side elevation thereof; Fig. 3, a horizontal section through the plunger portion of the press, taken as indicated by the line *x x* in Fig. 2; and Fig. 4 a further horizontal section, taken as denoted by the line *y y*.

Similar letters of reference indicate corresponding parts.

My invention has reference to presses for the perforation of shoe-tips and other parts of shoes or other articles, and it consists in novel means for holding or backing the punches.

Referring to the accompanying drawings, A represents the frame of the press, and B its bed.

C is the stem or body of the plunger, and D the lever by which it is operated through an eccentric, *a*, and link-motion *b*.

C' is a lower flange or plate portion cast on the plunger for the purpose of carrying in a steady and secure manner the punch-holder E, which is also of plate form, and is held by screws *f f* to the flange C'. To avoid making this flange C' and the stem C in separate pieces, which would be necessary where the plunger entered from above through the socket in which the stem works, I enter the same through the bed B of the press, to which end said bed is formed with a hole, *d*, through it, of sufficient size to allow of the flange C', as well as the stem C, being passed up through it, and this hole I cover with a steel die-plate, F, having perforations in it for the punches *e* to enter after their passage through the leather or material being worked. These punches *e* are of any required size and number, and arranged to form any particular pattern, the holes in the die-plate being made and arranged to correspond, according to the ornamental configuration it is required to give the tip or perforations therein. Said punches *e* are secured to the holder E by being driven into or through

it from below, and are backed at their tops by a steel plate, G, which is interposed between the flange C' and the holder, and which serves to prevent the upper ends of the punches from sinking or being worked by the punching action of the press into the softer cast-iron of the flange C'. The screws *f f* serve to secure the holder E and steel plate G to the flange C'.

H is a plate-punch stripper arranged at a suitable height, as regulated by washers *g g*, above the die-plate F, to allow of the introduction of the leather being worked over the latter. This plate-stripper is perforated to correspond with the punches, and to allow of the free passage of the same therethrough. It is arranged to extend across or over the die-plate, and being made of a thin steel plate secured at its ends by screws *c c*, which hold it and the die-plate to the bed, is necessarily elastic; but as it is important to prevent any binding action on the punches, that it should not spring, I stay it on opposite sides, at or near the middle of the length, by a pin, I, in front screwed into the frame, and a pin, I', in rear secured to said stripper, and bearing at its upper end under the socket portion of the main frame.

The stem C of the plunger is made round, which is a much easier shape to establish a true fit of it and the socket in which it slides than is a square form; but as in working a series of small punches extending over a large area, as is the case here, it is very important that there should be no turning or deviation in any way from a straight course of the plunger-stem. To counteract any possible failure in this respect as due to the round shape of the stem, I steady and guide the plunger at distant points on opposite sides by means of pin projections K K from or at the ends of the holder E, said pins playing, as the plunger is reciprocated, through holes *s s* in the stripper H and die-plate E.

What is here claimed, and desired to be secured by Letters Patent, is—

The combination of the steel plate G with the flange C' of the plunger, and with the punch-holder E and its punches *e*, essentially as and for the purpose herein set forth.

EDWIN B. STIMPSON.
